Henry Stanley   Design. Stove.
No 40   Patented: Oct 16th 1845.

Henry Stanley, West Poultney, Vermont.
Letters Patent (Design No 40) Dated 16th October 1845

The schedule referred to in these Letters Patent and making part of the same.

To all whom it may concern: Be it known that I, Henry Stanley, of West Poultney, in the County of Rutland and State of Vermont, have invented and produced a new and useful ornamental design for a stone, which ornamental design is represented in the Drawing which accompanies this application for a patent therefor, and description thereof. The front and end plates of my stone have the ornamental devices thereon, as shown at A, and B, and the shape or configuration, of the top plate and the ornaments thereon, are such as are seen on said top plate, and are marked C, C. This top plate I surmount with an ornamental urn, or vase, which is shown at D. This urn is made hollow, and has its top removable for the purpose of supplying the same with water when desired, but this I do not include in my claim to a patent, the same urn having been previously used by me.

I have thus described and represented the respective parts of my newly designed stone, so far as its configuration and ornament are concerned, and I claim the exclusive right to the use of plates A, and B, thus shaped and ornamented, also in the manner represented in the drawing; and also the particular shape and ornamental design of the top plate thereof, as aforesaid.
